UNITED STATES PATENT OFFICE.

ORIN W. SMIRL, OF WILSEY, KANSAS.

MAIL-DELIVERING APPARATUS.

1,268,400.

Specification of Letters Patent.

Patented June 4, 1918.

Application filed November 19, 1914. Serial No. 872,987.

To all whom it may concern:

Be it known that I, ORIN W. SMIRL, a citizen of the United States, residing at Wilsey, in the county of Morris and State 5 of Kansas, have invented certain new and useful Improvements in Mail-Delivering Apparatus, of which the following is a specification.

My invention relates to new and useful 10 improvements in a mail delivering apparatus.

The primary object of the invention is the construction of a device of this character wherein the mail is automatically delivered 15 from a train into a receptacle arranged along the track.

A further object of the invention is the provision of means for conveying the mail from the receptacle to any desired point 20 such as the post-office.

A still further object of the invention is the provision of means for automatically releasing the conveyer when the mail is received therein.

With these and other objects in view the invention consists in the novel details of construction and arrangement of parts which will be more clearly understood from 25 the following description and drawings, in which,

Figure 1 is a view in side elevation of the delivering and receiving mechanism, the car being shown in section.

Fig. 2 is a top view, parts broken away, 35 of the delivering mechanism carried by the car.

Fig. 3 is a front view of the receiving member.

Fig. 4 is a vertical section through the 40 receiver and conveying device.

Fig. 5 is a longitudinal sectional view of the conveyer.

Fig. 6 is a fragmental detail of the delivering device, and

Fig. 7 is a front view, partly in section, 45 of the tripping post.

In describing my invention I will divide the several parts into three sections, namely, the delivering mechanism carried by the car, 50 the receiving receptacle along the side of the track, and the conveyer for carrying the mail from the receiving receptacle to the

desired point for depositing, such as the post-office.

Delivering mechanism.

In the drawings, the numeral 1 indicates the ordinary mail car, and 2 a support upon which is secured a receptacle 3 open at the forward end, and a brace 4 which extends from the underside of the receptacle 3 to the support 2. Brackets 5 are secured to each side of the receptacle and extend in the rear thereof, and mounted in the rear end of the brackets is a rod 6 having the crank handle 7 on one end thereof. A ratchet wheel 8 is secured to the rod intermediate its ends. A second rod 9 is mounted in the brackets at a point between the end of the receptacle and the rod 6 and a pawl 10 is pivotally connected to the rod 9 and adapted to normally engage the ratchet wheel 8, as more particularly shown in Figs. 1 and 2 of the drawings.

Slidably mounted within the receptacle 3 is a plate 11 having the rollers 12 mounted in the top and bottom edges thereof and adapted to engage the top and bottom of the receptacle 3. Rods 13 are secured to the back of the plate and extend through the rear wall of the receptacle 3, as more clearly shown in Fig. 2 of the drawings, and nuts 14 are received on the ends of the rods. Washers 15 are also secured on the ends of the rod and are adapted to engage the end 85 of the receptacle 3 when the plate 11 is in its forwardmost position. Coil springs 16 surround the rods 13 between the plate 11 and rear wall of the receptacle.

Ropes or cables 17 are secured to the plate 11 by the eyes 18 and said ropes or cables pass through the rear wall of the receptacle 3 and are connected to the rod 6 upon which they are adapted to be wound by turning the handles 7.

A bracket 19 is secured to the top of the receptacle and hingedly connected to the bracket 19 is an arm 20. A rope or cable 21 is connected to the arm 20 and the free ends of the rope or cable extend in opposite directions, through the eyes 22 on the top of the receptacle 3, and are connected to the pawl 10.

Arranged along the track on each side

of the receiving receptacle, which will be later described, are the posts 23 having the heads 24 secured to the tops thereof.

Having described the detailed construction of the delivering mechanism it is thought that the operation will be clear. The mail bag indicated at 25, Fig. 2 of the drawings, is placed within the receptacle 3 bearing against the plate 11. The handle 10 on the rod 6 is turned thereby winding the ropes or cables 17 upon the rod and drawing the plate 11 toward the rear end of the box and placing the springs 16 under tension. The pawl 10 engaging the ratchet wheel 8 prevents the cable from being unwound until the pawl is released. As the train comes to the receiving receptacle, to be later described, the arm 20 which extends beyond the side of the car engages the head 24 on the post 23 and the arm is thrown to one side thereby pulling upon the cable 21 which releases the pawl 10 from the ratchet wheel 8. The springs 16 thereby force the plate 11 toward the front of the box and shoots the bag therefrom into the receiving receptacle. The heads 24 on the posts 23 are preferably formed in the shape shown whereby the arm 20 will be held for just that fraction of time so that the pawl will be held from the ratchet wheel sufficiently long for the bag to be delivered.

Receiving mechanism.

The receiving mechanism comprises a receptacle 26 upon the ground along the side of the track. Extending upwardly from the receptacle 26 is a chute member 27 which is preferably of the shape shown and open at the front, as indicated at 28. The chute 27 is preferably formed in sections connected by the strips 29, but I do not desire to limit myself to this particular construction. The receptacle 26 is preferably formed with a door 30 through which access is gained into the receptacle when desired.

The interior of the chute and receptacle are perfectly smooth so that there will be no injury to the bag when delivered therein.

The bag delivered from the train passes through the opening 28 and into the chute 27 from which it is deposited into the conveying device which will be later described.

Conveying mechanism.

The conveying mechanism comprises a receptacle 31, more clearly shown in Figs. 4 and 5 of the drawings, and this receptacle is mounted upon suitable wheels 32 which operate upon a track 33 leading from the post office or other building into the receiving receptacle 26. The receptacle 31 is adapted to be received within the receiving receptacle 26 and under the chute 27. The mail is deposited from the chute 27 into the receptacle 31. Secured within the receptacle 26 is a

bracket 34 and pivotally connected to the conveying receptacle 31 is a catch member 35 which is adapted to engage the bracket 34 whereby the receptacle 31 is held beneath the chute 27. A spring member 36, of the construction shown in Fig. 5 of the drawings, is secured to one end of the receptacle 31 and is adapted to be compressed between the ends of the receiving receptacle 26 and conveying receptacle 31 when said conveying receptacle is under the chute. A plate 37 is hinged to the side of the receptacle 31, as indicated at 38, and the receptacle is provided with a hinged cover 39, more clearly shown in Fig. 5 of the drawings. A coil spring 40 is connected to the plate 37 and cover 39.

The mail bag passes through the chute 27 and is deposited upon the plate 37 which is lowered by the weight of the bag and engages the end of the catch 35 thereby releasing it from the bracket 34. As the plate is lowered it lowers the cover 39 over the receptacle. As soon as the catch 35 is released from the bracket 34 the spring 36 shoots the receptacle forward and as the tracks 33 are inclined the receptacle rolls to the desired building, such as the post-office.

Having fully described the several elements of the invention it is thought that the advantages will be clearly understood. As stated above, a post 23 with the head 24 is placed upon each side of the receiving receptacle 26 so that the delivering mechanism may be operated when the train is passing in either direction. The mail is automatically delivered from the train and deposited into the receiving receptacle from which it is conveyed to the desired point.

It will be seen that the arm 20 of the delivering device may be swung within the car when it is not desired to deposit mail.

Having fully described the invention what I claim as new and desire to secure by Letters Patent is:—

1. In a mail delivery apparatus, a receptacle carried by a car, and having a plunger operating in the receptacle, rollers mounted on the plunger and engagable with the top and bottom of the receptacle to maintain the plunger in movable position in the center of the receptacle, rods secured to the plunger and passing through the receptacle and having springs interposed between the plunger and receptacle, a rod secured to the receptacle, the said rod and plunger having cables connecting them together, means for rotating the rod, means for holding the rod against rotation, and means for releasing the rod.

2. In a mail bag delivering apparatus, the receptacle carried by a car, a plunger operating in the said receptacle and provided with rods passing through the end of the receptacle, said rods having springs interposed

between the plunger and the said receptacle, the latter being provided with brackets, a rod rotatably mounted in the bracket and carrying a ratchet wheel, cables secured to the plunger and coiled about the said rod, a pawl secured to the brackets and engagable with the ratchet wheel, and an arm pivotally connected to the receptacles, the said arm

and pawl having means for releasing the said rod. 10

In testimony whereof I affix my signature in presence of two witnesses.

ORIN W. SMIRL.
